FUEL REGULATING SYSTEM

Louis Schelfhout, Chicago, Ill.

Application January 13, 1936, Serial No. 58,826

3 Claims. (Cl. 236—20)

My invention relates to a fuel regulating system for boilers, furnaces, or the like, and it has to do more particularly with mechanism for regulating the opening and closing of damper structure.

One of the objects of my invention is to provide an improved system of the foregoing character.

Another object is to provide an improved arrangement for controlling the operation of stack damper structures.

Still another object is to provide a control system of the foregoing character wherein means are provided for retaining the boiler heat during non-fuel-feed periods by minimizing heat loss through the boiler stack; increasing the length of non-fuel-feed periods; decreasing the frequency of fuel feed periods; and reducing fuel consumption of the furnace.

A further object is to provide in a system of the foregoing character including fuel feeding means and a forced draft means, an improved stack damper control wherein the damper is opened and closed in timed relation to the cutting in and out, respectively, of the fuel feed and the forced draft means.

Other objects are to provide a furnace, boiler, or the like, regulating system that is quite simple in construction, is easy to install and maintain, is automatic in operation requiring a minimum of attention, reduces fuel waste to the minimum, and which insures greater efficiency in the operation of the furnace at a much reduced cost.

Other objects and advantages will become apparent as this description progresses and by reference to the drawings wherein,—

Figure 1 is a side elevation of a furnace having one form of regulating mechanism embodying my invention applied thereto;

Fig. 2 is a front elevational view of the structure shown in Fig. 1;

Fig. 3 is a diagram illustrating the electrical circuit and its relation to the operating parts of the structure shown in Figs. 1 and 2;

Fig. 4 is an enlarged section taken substantially on line 4—4 of Fig. 2 and showing the damper actuating device which is pneumatically operated; and

Fig. 5 is a view partly in section of a modified form of damper actuating device which is electrically operated.

In the drawings, I have illustrated my invention as applied to a hot water heating boiler 10 having a fire-box (not shown) to which fuel (in this instance coal) is fed by an underfeed type of

stoker 11 connected to the front of the boiler by conduit 12. The feed conduit 12 may contain any suitable form of feeding means such, for example, as a screw conveyor (not shown) driven by an electric motor 13. It will be understood, however, that any other type of boiler or furnace may be used, and any other type of feeding means having utility in connection with my invention may be employed without departing from my invention.

In the use of fuel feeding structures of the foregoing character, it is customary to employ forced draft means and, to that end, I employ a fan-type blower 14 driven by an electric motor 15 (Fig. 3) and connected to the boiler firebox by a conduit 16 (Fig. 1). The blower 14 is preferably located at the rear of the boiler structure independently of the stoker 11, but it will be appreciated that it may also be directly associated with the stoker at the front of the boiler, or it may be connected with the boiler at any other suitable point.

The boiler structure is further provided with a flue or stack 17 in which there is located a damper 18 pivotally supported by a shaft 19 in the wall of the stack (Fig. 1). The shaft 19 projects through the wall of the stack for reception of an actuating arm 20 which, as will be described more particularly hereinafter, is adapted to be actuated to swing the damper 18 to open and closed positions.

The boiler 10 further includes a chamber 21, or the like, adapted to contain water 22 which is heated by the boiler to desired extent for any desired purpose. The structure illustrated is particularly adapted for a house-heating system.

In the use of structures of the character just described, it is desirable that the fuel feed and the forced draft be cut out when the water, or other medium to be heated, reaches a desired temperature and I accomplish this in the following manner: The stoker motor 13 and blower motor 15 are connected in series in an electrical circuit indicated by the numerals 23, 24, 25, 26 and 27. This circuit is controlled by a switch 28 which may take any suitable form and may be manually or automatically controlled or both. Another and thermostatically-controlled switch 29 is also located in the electrical circuit in series with the motors 13 and 15. The switch 29 may take any suitable form controlled by a thermostatic element 30 disposed in the chamber 21 in contact with the water therein. The thermostatic element is preferably of standard form connected to the switch 29 in such a way that, when

the temperature of the water reaches a certain point, it will open the switch 29 and the electrical circuit thereby cutting out the motors 13 and 15 and stopping the fuel feed and forced draft. Also, when the temperature of the water is lowered below a certain point, the thermostatic element 30 functions to permit closing of the switch 29 thereby closing the electrical circuit and cutting in the motors 13 and 15 and starting fuel feed and the forced draft. The thermostat and switch control 29, 30 may take any suitable and well known form which is adjustable to cut in and out at variable water temperatures. The switch 28 may be termed a line or main power switch, and is usually cut in constantly, unless some over-load condition takes place, so long as it is desired to keep the boiler in operation.

It will be seen that the foregoing, in initially starting the boiler in operation, the switch 28 is closed and the stoker 11 and fan blower 14 are actuated to feed fuel to the furnace and to apply the forced draft thereto. As soon as the temperature of the water in the boiler reaches a predetermined temperature, the thermostat switch 29 will open and cut out the fuel feed and draft means until the temperature of the latter is reduced to a predetermined point, as above stated, at which time the fuel feed and draft are again cut in, and this operation is continued over and over again.

When the fuel feed is cut in and the fan blower is in operation, proper draft conditions require that the stack damper 18 be open. When the fuel feed is stopped, it is desired to conserve the boiler heat as far as possible and for that purpose it is desirable that the damper 18 be closed at this time to minimize heat loss through the stack 17. If the opening and closing of the damper 18 is accomplished manually, the constant attention of an operator is required, due to the cutting in and out of the feed as described; otherwise a considerable waste of fuel will take place and the stoker mechanism will be worked at its maximum due to the frequency of feed cut-in periods and the shortness of the feed cut-out periods.

My invention contemplates the provision of means for automatically opening and closing the damper 18 in direct timed relation to the cutting in and out of the fuel feed and the forced draft. This is accomplished in accordance with my invention by inserting damper control means in the electrical circuit in series with the motors 13 and 15 and the switches 28 and 29. In the operation of structures of this character, it is found that best results are obtained by having the damper open simultaneously with the beginning of fuel feed and the beginning of forced draft application and to have it completely closed by the time that the fuel feed is stopped and the forced draft is no longer applied. In the use of the fan blower above described, there is a continuing but gradually reducing rotation of the fan 14 due to its own momentum after the circuit to its motor 15 is opened so that the forced draft is applied for a short time after the fuel feed is stopped, and to take care of this condition, I provide a damper control arrangement whereby the closing movement of the damper 18 is accomplished with a somewhat delayed action to compensate for the delayed draft cut-off.

In carrying out the foregoing features of my invention, I may employ a comparatively small air compressor 31 driven by a motor 31^a connected in the electrical circuit in series with the

motors 13 and 15, so that when the circuit is opened by the switch 29 the motor 13 and air compressor will be stopped simultaneously with the cutting out of the fan blower and the fuel feed.

The air compressor 31 supplies air through a pipe 32 to a bellows-type diaphragm 33 having its lower edge secured to the bottom 34 of a casing 35 in sealed condition with respect thereto. The top of the casing 35 is provided with an upstanding lug 36 pivotally supporting, as at 37, a lever arm 38. The top of the diaphragm 33 is also provided with a lug 39 projecting upwardly through the top of the casing 35 and pivotally connected to the lever arm 38 as at 40 to one side of the pivot support 37. The right-hand end of the lever arm 38 (as viewed in Figs. 1 and 4) is connected to a chain 41 passing over a pulley 42 and connected to one end of the damper arm 20. The other end of the lever arm 38 supports weight members 43 which may be adjusted along the lever arm toward and from the pivot 37 to vary somewhat the rapidity of the collapsing action of the diaphragm 33 under conditions which will now be described.

When the air compressor motor is cut in along with the feed and blower motors 13 and 15, air is immediately supplied to the then-collapsed diaphragm 33 raising the weighted end of the lever arm 38 and lowering its other end to swing the damper arm 20 and damper 18 to an open position. The air compressor 31 maintains the desired pressure within the diaphragm 33 to hold the damper full open so long as the fuel feed means is cut in, and any suitable means (not shown) may be employed for intermittently cutting in and out the air compressor independently of opening of the main electrical circuit so that substantially a predetermined pressure is maintained in the diaphragm by the compressor. However, when the main circuit 23-27 is opened by the switch 29 (or switch 28) and the fuel feed is stopped, the compressor 31 is simultaneously stopped and air is exhausted from the diaphragm 33 and through the compressor structure by virtue of the natural looseness of the operating parts of the latter. If found desirable, though, special provision may be made for bleeding air from the diaphragm when the compressor is stopped. When the compressor is stopped, the weights 43 on the lever arm 38 cooperatively with the weight 44 on the damper arm 19 (opposite its chain connection) lower the weighted end of the lever arm 38, raising its other end and closing the damper 18. This action is a delayed one because of the time required for exhausting of air from the diaphragm 33 through the compressor structure and this delayed action, together with the rate of admission of air to the diaphragm 33, is controlled by a needle valve 45 in the compressor casing cooperating with a restricted opening 46 between the compressor chamber 47 and the pipe 32. In this way, the damper will move gradually toward its closed position and this action is delayed to such an extent that the damper is not fully closed until the fan blower 14 has completely stopped and a forced draft is no longer applied to the boiler. On the other hand, the cutting in of the air compressor 31 immediately builds up a sufficient pressure within the diaphragm 33 to cause opening movement of the dampers above explained practically simultaneously with the starting of the fan blower 14 and the fuel feed.

In certain cases, I may employ the electrical

control means illustrated in Fig. 5 for opening and closing the damper. This structure includes a lever arm 50 similar to the lever arm 38 and connected to the stack damper as by the chain 41 of Fig. 1. The lever arm 50 is reciprocated about its pivot 51 by a solenoid 52 having its core stem 53 pivotally connected to the arm 50 as at 54. The solenoid is supported by a suitably located bracket 52a. The solenoid stem is provided 10 with a piston member 55 operable in the chamber 56 formed in the casing 57 which serves to guide the movement of the solenoid stem in actuating the arm 50. Upward or opening movement of the solenoid stem is cushioned by a floating spring 15 58 freely surrounding the stem 53, and free movement of the piston 55 in both directions is permitted by bleed openings 59 and 60 in the casing 57. If desired, the upward or opening movement of the solenoid stem 53 may be further cushioned 20 by a needle valve 61 adjustably mounted in the casing 57 for variably controlling the exhaust of air from in front of the piston 55 to and through the casing opening 60. A similar arrangement (not shown) may be used, if desired, in connection 25 with the opening 60. The solenoid is located in the main electrical circuit in series with the feed and fan motors similarly to the air compressor motor of the first-described form. When the circuit is closed, as previously described, the 30 solenoid is energized raising its stem 53 to open the damper and vice versa when the main circuit is opened and the solenoid is de-energized.

I believe that the operation and advantages of my invention will be obvious from the foregoing. 35 The arrangement that I employ is quite simple, but effective in operation. The stack damper is closed only under no draft conditions, and it is quickly opened to accommodate draft conditions when the fuel feed is started. This feature 40 of my invention conserves boiler heat and increases the length of the feed cut-out periods and, consequently, decreases the frequency of the feed cut-in periods. Such an arrangement tends to eliminate the human element in the operation of the boiler, and it cuts down the cost of operation 45 not only from that standpoint but also by reducing fuel waste to the very minimum.

It is to be understood that, although I have shown and described only two forms of my invention, other changes in details and arrangements of parts may be resorted to without departing from the spirit and scope of my invention as defined by the claims that follow.

I claim:

55 1. In a system of the class described for a furnace, boiler, or the like, having a water heating chamber and a stack with a damper therein, a fuel feeder, a forced draft device, a damper actuator, motor means for operating said fuel feeder, draft device and damper actuator, connected in series in an electrical circuit, a thermostat device in said water chamber, and a switch in said electrical circuit in series with said motor means and actuated by said thermostat device to open said circuit to cut out said feeder and draft device and to close said damper when the

water in said chamber reaches a certain temperature and vice versa when the temperature of said water is lowered below a certain point, said damper actuating device being constructed to delay the closing action of said damper to approximately accommodate the gradual reducing draft applied by said draft device under its own momentum when its motor means is cut out of operation. 5

2. In a system of the class described for a 10 furnace, boiler or the like, having a heating chamber and a stack with a damper therein, a fuel feeder, a forced draft device, a damper actuating means including a member connected to said damper and fluid pressure supply means 15 adapted by the direct application of fluid pressure to said member to move the latter to open said damper, which said member is moved by the release of fluid pressure therefrom to close said damper with a delayed movement, motor means 20 for operating said fuel feeder, draft device, fluid pressure supply means, connected in series in an electrical circuit, a thermostat device associated with said chamber, and a switch in said electrical circuit in series with said motor means 25 and actuated by said thermostat to open said circuit to cut out said feeder and draft device and also to cut out said fluid supply means to close said damper when a certain predetermined temperature condition is reached in said chamber and vice versa 30 when the temperature condition in said chamber is lowered between a predetermined point, said member and fluid pressure means being so constructed and arranged that said delayed closing action approximately accommodates the gradual reducing draft applied by said draft device under its own momentum when its motor means is cut 35 out of operation. 35

3. In a system of the class described for a 40 furnace, boiler, or the like, having a water heating chamber and a stack with a damper therein, a fuel feeder; a forced draft device; a damper actuator comprising a reciprocable member, a connection between said member and said damper and an electrical device for actuating said member when said electrical device is energized so as to move said damper to and hold it in an open position; motor means for operating said fuel feeder and draft device, said motor means and said electrical device being connected in series 45 in an electrical circuit; a thermostat device in said water chamber; and a switch in said electrical circuit in series with said motor means and said electrical device and actuated by said thermostat device to open said circuit to cut out 50 said feeder and draft device and to deenergize said electrical device to close said damper when the water reaches a certain temperature and vice versa when the temperature of said water is lowered below a certain point, said damper 55 actuating device operating to delay the closing action of said damper to approximately accommodate the gradual reducing draft applied by said draft device under its own momentum when its motor means is cut out of operation. 60 65

LOUIS SCHELFHOUT.
